UNITED STATES PATENT OFFICE.

JOHN HANSEN, OF GREENWICH, CONNECTICUT, ASSIGNOR TO ABENDROTH BROTHERS,
OF PORT CHESTER, NEW YORK, A CORPORATION OF NEW YORK.

DESIGN FOR A GAS RANGE.

Application filed June 15, 1927. Serial No. 22,438. Term of patent 7 years.

To all whom it may concern:

Be it known that I, JOHN HANSEN, a citizen of the United States, residing at Greenwich, county of Fairfield, State of Connecticut, have invented a new, original, and ornamental Design for a Gas Range, of which the following is a specification, reference being had to the accompanying drawing, forming part thereof.

The figure is a perspective view of a gas range showing my new design, the dominant feature of which is the shape of the base thereof.

I claim:
The ornamental design for a gas range, substantially as shown and described.

JOHN HANSEN.
